UNITED STATES PATENT OFFICE.

SAMUEL MCELROY, OF BROOKLYN, NEW YORK.

FISH-PRESERVE DAM.

SPECIFICATION forming part of Letters Patent No. 450,490, dated April 14, 1891.

Application filed October 23, 1890. Serial No. 369,124. (No model.)

To all whom it may concern:

Be it known that I, SAMUEL MCELROY, of Brooklyn, in the county of Kings and State of New York, have invented a new and Improved 5 Fish-Preserve Dam, of which the following is a full, clear, and exact description.

The object of the invention is to provide a new and improved dam specially designed for streams, ponds, &c., containing game-fish, and 10 which permits the free discharge of the ordinary and extraordinary stream and storm flow without permitting escape of the fish.

The invention consists of an auxiliary weir adapted to discharge into the outlet-chute of 15 the ordinary weir.

The invention also consists in certain parts and details and combinations of the same, as will be fully described hereinafter, and then pointed out in the claims.

20 Reference is to be had to the accompanying drawings, forming a part of this specification, in which similar letters of reference indicate corresponding parts in all the figures.

Figure 1 is a sectional side elevation of the 25 improvement on the line 1 1 of Fig. 2. Fig. 2 is a plan view of the same, and Fig. 3 is a transverse section of the same on the line 3 3 of Fig. 2.

The improvement is provided with a suitably-constructed dam A, in which is arranged 30 transversely a chute B, formed by the two parallel side walls B' B², extending through the dam A from the bottom of its downstream A' to the upstream side A². The upper ends 35 of the walls B' B² are connected with each other by a head or cross wall B³, arranged to such a height as to form the ordinary overflow into the chute B. In the latter is arranged an inclined bottom B⁴, connecting at 40 its upper end with a suitable step B⁵, formed at the inside of the cross-wall B³. The lower end of the inclined bottom B⁴ extends a suitable distance and terminates at a transverse or cross wall B⁶, extending above the lower 45 end of the inclined bottom B⁴, which forms a water-pool and overflow for the flow of water passing down the inclined bottom B⁴.

In order to prevent game-fish contained in 50 the water of the pond or stream on the upstream side of the dam A from escaping through the chute B, a screen C is placed be-

tween the walls B' B² on top of the cross-wall B³. The chute B, with its screen C, forms the ordinary weir. A wall D, of semicircular or other form, is built on the outside of the wall B' at the upstream side of the dam A, the top of the wall extending a suitable distance above the top of the cross-wall B³, as plainly shown in Figs. 1 and 3. This wall forms a basin E, the bottom of which extends horizontally, and its opening on the front side is into the chute B. The horizontal bottom of this basin E is in line with the top of the projection B⁵, on which the inclined bottom B⁴ terminates. A step E' is formed on the inside of the wall D at a suitable height below its top, as is plainly shown in the drawings, so as to break the fall of the water when overflowing the top of the said wall D. On the top of the latter is built a suitable number of 70 piers D', between two adjacent ones of which is set a wire screen F F' F² F³, similar in construction to the screen C and extending to about the same height as the latter. The end screens F and F³, as is plainly shown in Fig. 75 2, have their inner ends set into suitable recesses formed on the outside of the wall B', the other end being in the corresponding piers D'. This additional wall D, with its screens F F' F² F³, forms an auxiliary weir, 80 which opens into the chute B by its basin E. Now it will be seen that as long as the water in the pond or stream at the upstream side of the dam A rises normally the overflow passes over the cross-wall D³ through the 85 screen C into the chute B. When a heavy storm or flood sets in, the water naturally cannot be quickly discharged over the cross-wall B³, and consequently the water rises until it finally passes over the wall D through 90 the screens F F' F² F³ into the basin E and from the latter into the chute B below the cross-wall B³. Thus a suitable outlet is provided in case of storm-flow without permitting fish to escape, as the screens C F F' F² F³ 95 prevent this.

As shown in the drawings, the dam A is provided on top with a roadway G, formed by an arch spanning the chute B. Alongside the latter is also formed a gate-house H by building a third wall I parallel to the wall B², as is plainly shown in Fig. 2. Between the walls

B² and I are arranged suitable gates J, so that the water from the pond or stream can flow between the upper part of the walls I and B². A transverse wall K is built between the walls B² and I. Below the gates J and through this wall K pass pipes L for carrying off water when the gates J are raised.

It is understood that the several walls, the sides of the dam, &c., are lined by proper material, such as cement masonry. It is also understood that in the ordinary weir, as at present constructed, the screen C has to be removed in order to give proper vent to the water in case of a storm-flow, so that game-fish could easily escape over the cross-wall B³. By making the auxiliary weir a sufficient outlet for any surplus water is furnished. At the same time fish cannot escape. It will further be seen that the discharge of the water through the chute B is greatly facilitated by the inclined bottom B⁴, which increases the velocity of the water passing over the cross-wall B³ and the auxiliary wall D.

Having thus described my invention, I claim as new and desire to secure by Letters Patent—

1. In a fish-preserve dam, a chute extending transversely through the dam and comprising two parallel side walls, a cross-wall on the upstream side of the dam, an inclined floor extending from the said cross-wall downward to a suitable distance below the crest of the dam, and a screen arranged on top of the said cross-wall, substantially as shown and described.

2. In a fish-preserve dam, an auxiliary weir adapted to discharge into the outlet-chute of the ordinary weir, substantially as shown and described.

3. In a fish-preserve dam, the combination, with the ordinary weir, of an auxiliary weir arranged on the upstream side of the dam alongside the said ordinary weir and adapted to discharge into the same, substantially as shown and described.

4. In a fish-preserve dam, the combination, with an ordinary weir having a chute with an inclined bottom, of an auxiliary weir having its top arranged above the ordinary weir and forming a basin discharging into the said chute, substantially as shown and described.

5. In a fish-preserve dam, the combination, with an ordinary weir, of an auxiliary weir having its top arranged above the top of the ordinary weir, substantially as shown and described.

6. In a fish-preserve dam, the combination, with an ordinary weir, of an auxiliary weir having its top arranged above the top of the ordinary weir, and a basin formed in the said auxiliary weir and discharging into the outlet-chute of the said ordinary weir, substantially as shown and described.

SAMUEL McELROY.
